FISH BAIT BASKET

Benedict J. Giordano, Hasbrouck Heights, N.J.
(123 Park St., Ridgefield Park, N.J.)

Filed Oct. 3, 1963, Ser. No. 76,860

Term of patent 14 years

(Cl. D31—4)

FIG. 1.FIG. 2.FIG. 3.FIG. 4.FIG. 1 is a front perspective view of a fish bait basket embodying my new design,

FIG. 2 is a rear perspective view,

FIG. 3 is a top plan view of the design with the cover open, and

FIG. 4 is an end elevational view.

The undisclosed bottom side of the basket is substantially flat and unornamented.

I claim:

The ornamental design for a fish bait basket, substantially as shown and described.
